UNITED STATES PATENT OFFICE.

MALNOR A. SHUMARD AND MALNOR A. SHUMARD, JR., OF HAOKE RANCH, NEAR BOERNE, TEXAS.

DESIGN FOR A TOBACCO-POUCH.

49,583.

Specification for Design.

Patented Aug. 29, 1916.

Application filed October 12, 1915. Serial No. 55,583. Term of patent 14 years.

To all whom it may concern:

Be it known that we, MALNOR A. SHUMARD and MALNOR A. SHUMARD, Jr., citizens of the United States, residing at Haoke Ranch, near Boerne, in the county of Kendall, State of Texas, have invented a new, original, and ornamental Design for Tobacco-Pouches, of which the following is a specification, reference being had to the accompanying drawing, in which—is a side view thereof. Fig. 3 is a rear elevation thereof, and Fig. 4 is a top plan view thereof.

We claim:

The ornamental design for a tobacco pouch, as shown.
